UNITED STATES PATENT OFFICE.

FRANK HINMAN PIERPONT, OF HORLEY, ENGLAND, ASSIGNOR TO LANSTON MONOTYPE MACHINE COMPANY, OF PHILADELPHIA, PENNSYLVANIA, A CORPORATION OF VIRGINIA.

MATRIX-HOLDER FOR TYPE-CASTING MACHINES.

1,307,698.

Specification of Letters Patent. Patented June 24, 1919.

Application filed October 20, 1917. Serial No. 197,656.

To all whom it may concern:

Be it known that I, FRANK HINMAN PIERPONT, a citizen of the United States, residing at Horley, county of Surrey, England, have invented certain new and useful Improvements in Matrix-Holders for Type-Casting Machines; and I do hereby declare the following to be a full, clear, and exact description of the same, reference being had 10 to the accompanying drawings, forming a part of this specification, and to the characters of reference marked thereon.

This invention relates to matrix holders for type casting machines of the class illustrated in Letters Patent No. 625,998, dated May 30th, 1899 and well known commercially as manufactured by Lanston Monotype Machine Company, and refers particularly to holders for display-type matrices to 20 be employed in connection with such type casting machines to enable them to be used for display-type casting.

Display-type are, as a rule, of greater dimensions than type designed to be used 25 in the production of composition or composed matter, or they are of a character which it is not desirable to produce from the regular matrix equipment provided for normal composition, because of the infrequency with which the characters are used, and hence it becomes desirable to provide 30 the machine with means whereby the display type matrix holder may be quickly and conveniently substituted for the regular matrix holder or die case and with means whereby the display matrices themselves may be 35 easily and conveniently changed so as to give a maximum capacity with a minimum labor on the part of the attendant.

40 The type matrix employed in the production of display type and designed to be held in the devices forming the subject matter of the present invention is well known, being illustrated, for example, in Letters Patent 904,510 dated November 24th, 1908; in this patent there is also shown a matrix holder of the general kind to which the present invention refers.

45 The holder of the present invention is constructed to take the place of the matrix holder provided for normal composition, and is adapted to fit into the guides for such holder provided on the casting machine, the machine for which the holder is especially

adapted being clearly set forth in said Letters Patent #625,998 above referred to; and the objects of the invention are generally to provide a matrix holder in which a plurality of matrix clamping members directly engage with the matrix each being independently spring-controlled, a holder equipped with temperature controlling means and having means whereby the position of the matrix contained in the holder may be varied with respect to the mold in connection with which the matrix is used.

Referring to the accompanying drawings throughout which similar parts are indicated by the same reference characters, Figure 1 is a bottom plan view of a 70 matrix holder embodying the present invention.

Fig. 2 is a sectional view, the section being taken substantially on the line 2-2 of Fig. 1.

Fig. 3 is a top plan view and

Fig. 4 is a section, somewhat enlarged, substantially on the line 4-4 of Fig. 3.

The body portion or frame 1 is provided with side ribs 2 and 3 to permit the 80 holder to be substituted for the usual matrix holder of the casting machine. The frame 1 is provided on its under face with two stationary gaging projections 4 and 5 at right angles to each other. The matrix A which is of rectangular form has two gaging edges 4' and 5' formed on sides at right angles to each other and adapted to bear against the gaging projections 4 and 5 respectively; the matrix A is also provided with two clamping edges 6' and 7' preferably beveled and located at diagonally opposite corners of the matrix, these edges 85 cooperating with spring controlled clamping devices. The latter consist of a plunger 8 provided with a matrix engaging clamping jaw 9, the plunger being guided in a hollow rib 10 and being directly acted upon by a spring 11; and a lever 12, pivoted to the frame at 13 and provided with a matrix engaging clamping jaw 14 and an operating handle 15, a spring 16, acting directly upon the lever 12. The spring 11 is held by the screw 16' so as yieldably to maintain the jaw 9 of the plunger 8 in advanced or 105 clamping position. The plunger 8 is also provided with a projection 17 (see Fig. 3) which is guided by the walls of the slot 18

in the matrix holder frame, such arrangement being provided to prevent the turning of the plunger in its guiding rib 10 and to assure of the correct position of the clamping jaw 9.

The spring 16 is held by the screw 19 so as to exert pressure on the bolt 20 guided in the frame rib 21 and engaging at its outer end with the lug 22 of the lever, thus tending yieldably to maintain the lever with its clamping jaw 14 in advanced or matrix clamping position. The spring 16 exerts a greater pressure than the spring 11, the main purpose of the latter and the clamping jaw 9 being to hold the matrix A to its seat and allow or compensate for any slight irregularity in the construction of the body of the matrix.

The guiding extension 23 of the frame 1 is provided with a stop or projection 24 for engagement with the lever handle 15 to hold said lever with its jaw in retracted position.

To place a matrix upon its seat or remove it therefrom, the handle 15 is moved to turn the lever on its pivot 13 and draw the clamping jaw 14 to its retracted position. In this motion of the handle it is sprung over the stop 24 and may be positioned behind the stop, as shown in dotted lines in Fig. 1, to maintain the jaw 14 in retracted position. When a matrix has been placed on the matrix seat in approximately correct position, the handle is released from the stop and by means of the spring 16 the lever 12 is caused to take up the operative position shown in full lines in Fig. 1. In assuming this position the matrix is moved against the weaker spring 11 until its surfaces 4' and 5' have seated against the gage surfaces 4 and 5 respectively. The clamping jaws 9 and 14 are preferably undercut and engage with beveled portions 6' and 7' of the matrix.

The frame 1 is provided with a cavity 25 in communication with which are the rib channels 26 which terminate one on each side of the holder handle 27. The cavity may conveniently be formed by covering a cast or bored recess by a plate 28 pressed or otherwise secured in place in such manner as to prevent leakage. The cavity is in proximity to the matrix seat 29 and the temperature of the matrix is adapted to be controlled by circulating a temperature controlling fluid, such as water, through the channels 26 and cavity 25. The outside ends of the channels 26 may be connected by a flexible tube 26' or the like with a source of such fluid. The mold water cooling channels may, if desired, be thus placed in communication with the cavity 25, in which case the temperature of the matrix A may be maintained at about the same temperature as the mold.

The matrix is positioned accurately with respect to the mold of the casting machine 65 by the cone-hole 30 in the holder into which

cone-hole the centering pin of the casting machine is adapted to enter, as will be readily understood by those skilled in the art. It is at times necessary to vary the position of matrices as when their character depressions are differently located with respect to their gage surfaces 4', 5' or when a mold of point size different from the point size of the matrix is employed. According to the present invention this is accomplished by placing the cone-hole 30 in a movable plate 31. This plate is slidably mounted on the frame 1 and is provided with a series of apertures 32 each of which may by sliding the plate be alined with a corresponding aperture 33 in the frame. When two corresponding apertures are alined, a positioning pin or dowel 34 is screwed into the plate aperture, which is screw-threaded for the purpose, the shank of the pin extending into the frame aperture so as to prevent further sliding motion of the plate. When a pair of these apertures are alined no other pair is in alinement but a new adjustment of the plate is required to bring about such a condition. In this way the plate may be made to take up a variety of positions each of which is fixed and definite and each of which adjusts the cone-hole accurately for the particular mold and matrix used. The construction is such that a fine adjustment may be secured with the use of relatively large holes and a large and strong pin. When the positioning pin has been screwed into place the fastening screw 35, its shank screw-threaded into an aperture in the frame and extending through a slot 36 in the plate 31 and its head adapted to contact with the top walls of the plate surrounding the slot, is screwed down to assist in maintaining immovable the established relation between the plate and the frame.

I claim—

1. A matrix holder for type casting machines embodying a frame provided with stationary gaging projections at right angles to each other, a plunger provided with a matrix engaging clamping jaw, a spring acting directly upon said plunger for yieldably maintaining said jaw in advanced position, a lever provided with matrix engaging clamping jaw and a spring acting directly upon said lever for yieldably maintaining said last mentioned jaw in advanced position.

2. A matrix holder for type casting machines embodying a frame provided with stationary gaging projections at right angles to each other, a plunger provided with a matrix engaging clamping jaw, a spring acting directly upon said plunger for yieldably maintaining said jaw in advanced position, a lever provided with matrix engaging clamping jaw and a spring acting directly upon said lever for yieldably maintaining said last mentioned jaw in advanced position.

position, said last mentioned spring exerting greater power than said first mentioned spring.

3. A matrix holder for type casting machines embodying a frame provided with stationary gaging projections at right angles to each other, a plunger provided with a matrix engaging clamping jaw, a lever provided with a clamping jaw and with an operating handle, springs for yieldably maintaining said jaws in advanced positions and a stop for engagement with said handle to hold said lever with its jaw in retracted position.

15 4. A matrix holder for type casting machines, embodying a frame provided with stationary gaging projections and with a matrix seat having a cavity, spring controlled clamping devices, means for circulating a temperature controlling fluid through said matrix seat cavity, a movable cone-hole plate and means for securing said plate with

its cone-hole in a variety of positions with respect to the said gaging surfaces.

5. A matrix holder for type casting machines, embodying a frame provided with stationary gaging projections and a matrix seat, spring controlled clamping devices, a movable cone-hole plate and means for securing said plate with its cone-hole in a variety of positions with respect to the said gaging surfaces.

6. A matrix holder for type casting machines, embodying a frame provided with stationary gaging projections and a matrix seat, spring controlled clamping devices, a cone-hole plate, said plate and said frame being provided with a series of positioning apertures and said plate being slidably mounted on said frame to align an aperture therein with one of the apertures in said frame, and a positioning pin inserted into said aligned apertures.

FRANK HINMAN PIERPONT.
